UNITED STATES PATENT OFFICE.

FRANCIS J. WESTON, OF BINGHAMTON, NEW YORK, ASSIGNOR OF ONE-HALF TO
BERNARD L. GABRIEL, OF BINGHAMTON, NEW YORK.

PACKAGE.

1,089,889.

Specification of Letters Patent. Patented Mar. 10, 1914.

Application filed August 9, 1913. Serial No. 783,884.

To all whom it may concern:

Be it known that I, FRANCIS J. WESTON, a citizen of the United States of America, residing at Binghamton, in the county of 5 Broome and State of New York, have invented certain new and useful Improvements in Packages, of which the following is a specification, reference being had therein to the accompanying drawings.

10 This invention relates to packages and to an arrangement thereof whereby the contents can be readily removed from the same, being particularly adaptable for tobacco, snuff, cheese or like articles.

15 The object of the invention is to provide means whereby the contents of the receptacle may be lifted bodily from the bottom thereof so as to project beyond the mouth and thereby be readily detached or taken 20 out.

The invention consists in the matters hereinafter set forth and particularly pointed out in the appended claims.

In the drawings, Figure 1 is a view in 25 perspective, partially broken away and in section, of one form of package that embodies features of the invention; Fig. 2 is a perspective view of the preferred form of ejector; Fig. 3 is a similar view illustrating 30 a modified form of ejector; Fig. 4 is a similar view illustrating a still further modified form of ejector; Fig. 5 is a cross sectional view of a portion of the same illustrating a 35 method of attaching the lining of a package to the ejector, and Fig. 6 is a vertical sectional view of a portion of a casing, illustrating an ejector handle held by the lid or cover of the casing.

Referring to the drawings an ejector plate 40 1 is arranged to conform to the interior of a package so that when in lowest position it is substantially the false bottom therefor. A handle strip 2 is secured at proper position upon the margin of the ejector and extends up the interior wall of whatever receptacle, such as illustrated at 3, the device 45 may be applied to. The handle is preferably of pliable material whereby it may be folded over the upper margin of the receptacle between the cover flange 4 if there be 50 one and the side of the casing. Where the receptacle has a flexible lining 5 such as is common in packing tobacco and other commodities and may be of waxed paper or similar 55 material, the ejector has spurs 6 formed

on its margin which are arranged to be bent upwardly into the lining so as to retain the latter readily in place. As indicated in Fig. 3, the ejector may have a marginal flange 7 of considerable depth or it may have an inrolled rim 8 as shown in Figs. 4 and 5 which may be crimped down over the flexible lining 9 to retain the latter firmly in position.

As a preferred form of construction the 65 ejector body 1 and handle strip 2 with the spurs 6 or flanges 7 or 8 are formed of a one piece sheet metal blank cut and bent to shape. The upper portion of the handle strip may be permanently bent downwardly 70 and outturned for a finger pull 10 or may be bent down from time to time at different places so as to retain the ejector body at an interval from the bottom of the package as the contents of the latter is used. 75

In operation, the contents of the receptacle may be lifted bodily from the bottom thereof when the top is opened by drawing up on the handle strip so that the contents is either discharged from the mouth or, if 80 enclosed in a lining is projected beyond the receptacle mouth so as to be readily removable.

The device is particularly useful when applied to pocket packages containing tobacco or the like where it is difficult to insert the hand to remove the material in the lower portion of the casing. 85

Obviously, changes in the details of construction may be made without departing 90 from the spirit of my invention and I do not care to limit myself to any particular form or arrangement of parts.

What I claim is:—

1. The combination in a package having 95 a permanently formed outer casing, and a collapsible lining, of an ejector corresponding in form to the cross sectional contour of the package and provided with folding means for engaging the lower portion of the 100 collapsible lining, and a lifting handle intermediate the ends of said ejector and extending from the margin of the ejector upwardly between the lining and the casing wall.

2. The combination in a package having 105 a permanently formed outer casing provided with a lid, and a collapsible lining, of an ejector corresponding in form to the cross sectional contour of the package and provided with folding means for engaging the 110

lower portion of the collapsible lining, and a lifting handle extending from the margin of the ejector upwardly between the lining and the casing wall, the handle being adapted to be bent downwardly over the margin of the upper end of the casing and retained in engagement therewith by the lid of said casing.

3. The combination in a package having
10 permanently formed outer casing and a col-
lapsible lining, of an ejector corresponding
to the interior cross sectional contour of
the casing on which the lining rests, means
on the margin of the ejector for engaging
15 the adjacent portions of the lining, and a
handle formed integrally on the ejector that
extends upwardly between the lining and
the casing and is adapted to be bent down-
wardly over the margin of the casing.
- 20 4. A package comprising an outer casing

adapted to contain a lining, a flanged cover
closing over the upper open end thereof, an
ejector formed of sheet material having a
body formed substantially to the interior
cross sectional contour of the casing, and its 25
edges provided with means for engaging the
lining placed in said casing, and an up-
wardly projecting strip on its margin forming
a lifting handle that extends between
the lining and the casing and is bendable 30
downwardly over the upper margin of the
casing, the flange of the cover being adapted
to close over the handle.

In testimony whereof I affix my signature
in presence of two witnesses.

FRANCIS J. WESTON.
